(57) **CLAIM**

The ornamental design for an infant support top, as shown and described.

DESCRIPTION

FIG. 1 is a front view of an infant support top in accordance with the present invention in an example in use being worn by a user supporting an infant.

FIG. 2 is a front view thereof.

FIG. 3 is a back view thereof.

FIG. 4 is a right view thereof.

FIG. 5 is a left view thereof.

FIG. 6 is a top view thereof.

FIG. 7 is a bottom view thereof; and,

FIG. 8 is a front view of the infant support top worn with a hood up on a user's head.

The broken lines in FIGS. 1 and 8 depicting a user and infant using the infant support top are for illustrative purposes only. None of the broken lines for a part of the claimed design.
